APPARATUS FOR DISPLACING AIR FROM
FILLED CONTAINER HEAD SPACESAlfred L. Kronquest, Syracuse, N. Y., assignor to
Continental Can Company, Inc., New York,
N. Y., a corporation of New York

Application April 1, 1943, Serial No. 481,500

34 Claims. (Cl. 226—68)

The invention relates generally to the packaging of liquids and primarily seeks to provide novel means for displacing air from the head spaces above the liquid fill in containers in which liquids such as fruit and vegetable juices are being packaged, said displacement being accomplished by utilizing an inert gas in a manner for forming a small bubble foam in said head spaces effective to crowd out the air therefrom.

It has been found desirable in the packaging of fruit and vegetable juices to remove air from the head spaces in the containers and substitute therefor a gas that will not react with the juices or with coated or lined surfaces in the containers themselves. Nitrogen gas and carbon dioxide gas are examples of inert gases which are effective as air displacing media. The presence of the oxygen air in the container head spaces often deleteriously affects the flavor of the juices during sterilization or storage. It also oxidizes the vitamins in the juices, thus decreasing the vitamin content. Further, oxygen in the container head spaces has a deleterious effect on some enamels where the containers are lined with enamel to prevent the juices from directly contacting with the metal of the container. Also, when plain, non-coated containers are used, the oxygen in the head spaces often increases the solution of the metal from the containers, thus increasing corrosion, pinholing and resultant leaks. The desirability of providing apparatus which will operate efficiently to displace air from container head space should, therefore, be obvious.

Various attempts have been made to displace the air from container head spaces with only partial success. By one method a jet of inert gas was directed into the container head space, but this method not only resulted in unnecessary wastage of gas but also effected the desired air displacement only partially. It has been proposed to direct a jet into carbonated beverages such as beer, or to otherwise agitate such beverages, the agitation serving to produce large bubble foaming partially effective to displace air from the headspaces, but obviously such methods cannot be applied to fruit and vegetable juices which are not carbonated.

Therefore, it is the purpose of the present invention to provide a novel apparatus for directing an inert gas in finely dispersed form into each container just below the surface of the liquid therein so as to cause small bubbles to form closely adjacent the top surface of the liquid and gradually fill the head space and

crowd out the air therefrom just prior to the closing of the container.

An object of the invention is to provide an apparatus of the character stated which can be conveniently placed for delivering the treated containers directly to the closing machine and, if desired, also close to the filling machine so as to receive the filled containers directly therefrom, means being included for enabling adjustment of the apparatus to adapt the same for treating containers of different heights.

Another object of the invention is to provide an apparatus of the character stated in which is included inert gas dispersing elements, means to cause the elements and the containers to move together with an element centered over each container, means for bringing about relative movement between the containers and the elements to cause said elements to be immersed a limited distance in the liquid in the containers, travel along a distance with the containers and immersed therein and then be withdrawn from said immersion, and means for directing the inner gas into said elements.

Another object of the invention is to provide in apparatus of the character stated endless conveyor means supporting the gas dispersing elements, and means for always holding the elements uprightly on said conveyor while they are moving into, along with and out of the traveling containers.

Another object of the invention is to provide in apparatus of the character stated novel means forming a flexible conduit for feeding the inert gas to the gas dispersing elements as they are traveling with the endless conveyor.

Another object of the invention is to provide an apparatus of the character stated wherein there is included in the means for holding the gas dispersing elements uprightly, novel valve means operable to direct gas to the elements traveling along the lower flight only of the endless conveyor means, or in other words for directing gas only to those elements which are moving into, along with and in the process of being withdrawn from the traveling containers, thereby to minimize gas wastage.

Another object of the invention is to provide an apparatus of the character stated in which the means for moving and holding the gas dispersing elements uprightly includes two laterally spaced endless chains each traveling about two sprockets, the sprockets supporting one chain being rotatable about axes disposed in a horizontal plane below the plane in which the axes

of the sprockets supporting the other chain are located, said elements being elongated and each having two pivotal connections arranged in a common vertical plane and one connected with one chain and the other with the other chain, and the sprockets at each end of the cooperating chains having their axes disposed in a common vertical plane.

Another object of the invention is to provide an apparatus of the character stated in which the inert gas dispersing elements constitute removably mounted, hollow, thimble-like devices having porous metal or ceramic walls through which the inert gas filters in a multitude of minute jets effective to form small bubble foam in the liquid fill in which the elements are immersed.

Another object of the invention is to provide apparatus of the character stated including a container feed table for feeding the open containers in spaced relation, a gassing housing disposed above the feed table and including therein gas dispersing elements and means for causing said elements to move into the traveling containers, then along with the containers, then out of said containers, a vertically slidable frame standard supporting the housing, and means for imparting movement of adjustment to the standard to vary the vertically spaced relation of the feed table and the housing to adapt the machine for operation on containers of different sizes.

Another object of the invention is to provide an apparatus of the character stated in which the gas dispersing elements are supported on and moved by an endless chain and each said element includes a gas receiving nipple extension, and in which the means for supplying gas to the elements comprises a hollow rotor rotating in timed relation with the chain and having gas supplying nipple extensions equidistantly spaced thereon and equal in number to the chain borne nipple extensions, means to supply gas to said rotor, and flexible ducts connecting each nipple on the rotor with one nipple on the chain.

Another object of the invention is to provide an apparatus of the character stated in which the means for moving and holding the gas dispersing elements uprightly includes a single endless chain, spindles projecting horizontally from the chain, sleeves rotatably mounted on the spindles and from which said elements depend vertically, crank members projecting from the sleeves, and guide means for constantly holding the cranks in a definite relation to said elements thereby to constantly hold the elements uprightly.

With the above and other objects in view that will hereinafter appear, the nature of the invention will be more fully understood by following the detailed description, the appended claims and the several views illustrated in the accompanying drawings.

In the drawings:

Figure 1 is a plan view of an apparatus embodying the invention, the association thereof with a closing machine of the continuously moving turret type also being shown, somewhat diagrammatically.

Figure 2 is a side elevation of the apparatus shown in Figure 1.

Figure 3 is a vertical cross section taken on the line 3—3 on Figure 2.

Figure 4 is an enlarged horizontal section of

the apparatus housing at the end thereof adjacent to the closing machine.

Figure 5 is an enlarged horizontal section of the apparatus housing at the end thereof adjacent to the filling machine.

Figure 6 is an enlarged part side elevation and part vertical longitudinal sectional view of the apparatus housing at the end thereof remote from the closing machine.

Figure 7 is a vertical cross section taken on the line 7—7 on Figure 6.

Figure 8 is a fragmentary horizontal section illustrating the sprocket valve hub, valve actuator ring and clamp rotor assembly.

Figure 9 is a detail face view of the sprocket valve hub and valve actuator ring and clamp rotor assembly, the rotor and the supporting stud shaft being shown in section.

Figure 10 is a detail vertical cross section through one of the gas dispersing units.

Figure 11 is a plan view illustrating a modified form of the apparatus mounted directly on a closing machine of the single closing station type.

Figure 12 is a face view of the gassing apparatus shown in Figure 11.

Figure 13 is a plan view of the apparatus shown in Figure 12.

Figure 14 is a fragmentary enlarged part plan view and part horizontal section of the gas dispersing element supporting and conveying devices.

Figure 15 is a vertical longitudinal sectional view illustrating the parts shown in Figure 14.

Figure 16 is a vertical cross section taken on the line 16—16 on Figure 13.

Figure 17 is a vertical cross section taken on the line 17—17 on Figure 15.

Figure 18 is a detail plan view of one gas dispersing element supporting spindle and a section of the conveyor chain to which it is attached.

The invention may be incorporated in apparatus adapted for use with different forms of closing machines, those in which the containers are very rapidly closed while being carried on a continuously traveling turret, or those which operate less rapidly and include a single stationary closing station. An example of the first mentioned type of machine is illustrated in U. S. Letters Patent 1,752,912, issued April 1, 1930, to A. L. Kronquest, and an apparatus adaptable for being used in combination with this type of machine will first be described.

In Figure 1 of the drawings the cooperative relation of the improved apparatus and a closing machine of the type first above mentioned is diagrammatically illustrated. In this somewhat diagrammatic illustration a feed timing means is provided and designated A, the apparatus for displacing the air from the traveling container head spaces and which constitutes the present invention is generally designated B, the filled and gassed container feeding turret of the closing machine is generally designated C, and the closing machine turret is generally designated D.

The improved apparatus includes a floor stand 5 which supports an elongated feed table 6 including laterally spaced angle irons 7 and supporting slide rails 8 which are mounted on the elements 7 and which provide slide supports for the traveling containers 9.

The containers 9 are rapidly conveyed over the supporting rails 8 by suitably spaced feed lugs

10 on the feed chain 11, the effective or feeding flight of which travels over a supporting rail 12 disposed between the element 7 in the position best illustrated in Figure 3, suitable side guides 13 being provided for guiding the passage of the containers over the rails 8.

The chain 11 passes over and is driven by a sprocket 14, passes over a second end sprocket 17, idler sprockets 15, and tightener sprockets 16, and also over a sprocket 18 which forms a part of the drive for the moving parts of the gassing apparatus in a manner later to be described.

The gassing apparatus generally designated B is mounted on a supporting standard 19 which is slide guided as at 20 on the feed table frame 6 and has a rack 21 affixed thereto in a vertical position and which is engaged by an adjuster pinion 22 secured to one end of an adjuster shaft 23 rotatable in a fixed bearing provided therefor on the frame 6 and equipped with a hand wheel 24. It will be obvious by reference to Figures 1 and 2 of the drawings that by turning the hand wheel 24 in one direction or the other the skirt 19 and the apparatus supported thereon can be lifted or lowered so as to vary the spacing thereof above the container feedways 8 and thus adapt the machine for operating on containers of different heights.

The apparatus includes an elongated housing 25 secured to the upper end of the standard 19 and overlying the elongated feed table 6 in the manner clearly illustrated in Figures 2 and 3 of the drawings. The housing is provided with an elongated bottom opening defined by two laterally spaced, parallel rails 26 and 27. See Figures 3 and 7.

A cross shaft 28 is rotatably mounted in bearings 29 at the end of the housing 25 nearest the closing machine, and the shaft has two spur gears 30 adjustably secured thereon as at 31, one at each side of and within the housing. See Figure 4. A driver sprocket 32 also is secured on the shaft 28 and is adapted to be driven by a chain 33 which is in turn driven by a driver sprocket 34 on a cross shaft 35 rotatably supported as at 36 at a central upper portion of the housing 25, a tightener sprocket also being mounted for adjustable engagement with the chain 33.

The cross shaft 35 has a bevel gear 38 affixed thereto to which rotation is imparted by a driver bevel gear 39 secured to the upper end of a vertical shaft 40 rotatably supported in bearings 41 in the standard 19 and frame 6 and having a spline connection as at 42 in a bevel gear 43 which is rotatably supported in the lower one of the two bearings 41. See Figure 3. The bevel gear 43 and the shaft 42 splined therein are driven by a bevel gear 44 fixed on a cross shaft 45 which is rotatable in a frame bearing 46 and to which rotation is imparted by the previously described sprocket 18.

Each gear 30 within the housing 25 meshes with and drives a spur gear 47, and each gear 47 rotates idly about a stud shaft 48 secured to the respective adjacent housing wall. See Figure 4. Each idler gear 47 has a sprocket 49 fixed thereto, and it will be observed by reference to Figure 2 of the drawings that one of the stud shafts 48 is mounted at a higher level than the other of the shafts 48. An endless conveyor chain 50 passes over each sprocket 47 so as to provide lower and upper conveyor flights extending along within the housing and toward the end thereof remote from the closing machine. The lower flight of

each chain passes under an idler sprocket 51 mounted on a stud shaft 52 secured to the respective adjacent housing wall, and each idler sprocket is so placed with relation to the cooperating sprocket 49 as to dispose the lower flight portion extending between the respective sprocket sets 51, 49 horizontally, or in vertically spaced parallel relation to the underlying container supporting slide rails 8. It will be apparent by reference to Figures 2, 3 and 7 that the horizontal lower flights of the chains 50 travel in separate vertically spaced planes.

The highest placed of the two chains 50 passes over an ordinary idler sprocket 53 at the end of 15 the housing remote from the closing machine, said sprocket being rotatable about a stud shaft 54 secured to the adjacent housing wall as illustrated in Figures 5 and 7. This sprocket 53 cooperates with the idler sprocket 51 engaged by the 20 same chain in providing a downwardly inclined portion 55 in said chain. See Figures 2 and 6. The purpose in providing this downwardly inclined chain portion will be explained hereinafter. The downwardly inclined portion 55 merges into 25 the previously mentioned horizontal lower flight portion of the chain and the latter is suitably guided and supported on a rail 56 mounted on the housing bottom opening defining rail 27.

The other or lower chain 50 passes over a 30 sprocket 57 at the end of the housing remote from the closing machine, said sprocket being secured as at 58 to a specifically constructed valve hub 59 of which more will be said later. See Figures 6 and 7. The sprocket 57 also is disposed higher 35 than the idler sprocket 51 engaged by the same chain so as to provide a downwardly inclined chain portion 60 merging into the horizontal lower flight portion of the lower of the two chains 50.

40 At spaced intervals corresponding to the spacing of the feed lugs 10 on the feeder chain 11, the higher chain 50 has bracket elements 61 affixed thereto. See Figures 6 and 7. To each bracket element 61 an angled bracket member 62 is affixed, and each bracket member carries a pivot pin 63 which projects therefrom toward the center of the housing in the manner clearly illustrated in Figure 7. Each pin 63 rotatably supports a collar or sleeve 64 having a slot across the top thereof in which is positioned a keeper pintle 66 straddling the arms of a fork 67 which extends upwardly from a main hub or sleeve body 68 forming a part of one of the gas dispersing elements.

55 Each element hub or sleeve 68 includes a depending leg 69 having a central gas port 70 and a threadably mounted gas dispersing stem 71 which depends from the leg 69 and is secured thereto by a lock or jam nut 72. A gasket plug 73 of rubber 60 or other suitable yieldable material is mounted on the lower end portion of each stem 71 and serves as a removable friction mounting for a thimble 74 of porous metal or ceramic material which constitutes the gas dispersing element. 65 Each plug 73 is spaced a distance from the lower extremity of the thimble 74 removably mounted thereon in the manner clearly illustrated in Figure 7 and aids in defining a gas chamber at the lower extremity of the particular gas dispersing element.

70 Each gas dispersing element hub or sleeve 68 is rotatably supported on a spindle 75 having an axial gas port 76 and a radially disposed delivery port 77 always directed outwardly with respect to the orbital paths of the chains 50 so as to register

with the respective gas port 70 and gas dispersing stem 71 only during the travel along the lower flights of the chains 50 by which the gas dispersing elements are supported and caused to travel. Each spindle also includes a radially disposed gas supply port 78, and the ports 78 in the spindles always are directed inwardly with respect to the orbital paths of chains for a purpose that will later become apparent.

Each spindle 75 is equipped with a central flange 79 which is abutted at one side by the respective hub or sleeve 68 and at the other side by a generally rectangular valve block 80 which is secured on the spindle as at 81 in a manner for being compelled always to project in the direction of the gas supply port 78, that is, inwardly with respect to the orbital paths of chains 50. See Figures 6 and 7. Each block has a pair of sockets 82 for receiving mounting pins 83 which extend laterally from the lowermost of the chains 50, and an angle piece 84 is secured as at 85 to the outer face of each block and has its angled ear portion 86 apertured as at 87 for receiving the opposite end extensions of the pins 83. By reason of the connection of these blocks 80 with the mounting pins 83 on the lowermost of the chains 50 and the securing of the spindles 75 in said blocks said spindles are mounted on and caused to travel with said lowermost chain. It should also be apparent that because of the offsetting of one of the chains 50 upwardly with respect to the other chain and the attachment of the collars 64 on the uppermost chain and the engagement of said collars in the forks 67 extending upwardly from the sleeves 68, the gas dispersing elements are always held uprightly during the travel of the chains 50 so as to constantly dispose the gas dispersing thimbles 74 with their axes vertical. This holding of the gas dispersing elements always in the upright position also cooperates with the arrangement of the delivery ports 77 in providing for gas delivery into the thimbles 74 only during the lower flights of the chains.

Each block 80 is provided with a valve chamber 88 in communication through a port 89 with the supply port 78 of the respective spindle 75. In each chamber there is mounted a valve ball 90, and each ball is pressed by a spring against a circular seat 91 in a seat plate 92 which is screw secured as at 93 to one side face of the respective block. Each time a block 80 is caused to travel around the sprocket 57 and the attached specially constructed valve hub 59 its ball 90 is unseated by engagement with a valve actuator ring 94 secured to the hub 59 by the same screws 58 which secure the sprocket 57 thereto. See Figures 6, 7 and 8.

The ring 94 is provided with two diametrically oppositely disposed arcuate ports 95 so shaped as to communicate with the valve seat openings and provide a solid wall contact with the ball and yet avoid causing the ball to ride over the arcuate opening. In other words, each arcuate port 95 is disposed in an arc struck from a center approximating the point at which the valve balls 90 engage the ring and on a radius less than the ball diameter, as will be apparent by reference to Figures 6 and 7 of the drawings. Each arcuate port communicates with a hub duct 96 including a radial leg 97 disposed to communicate with an arcuate cutout 98 in the sprocket and hub supporting stud shaft 99 secured to the housing in the manner clearly illustrated in Figure 7. It will be observed that the stud shaft includes an axial duct 100 adapted to be connected with the gas

supply source (not shown) so as to supply gas through the porting 97, 96 and 95 into the valve chambers 88 whenever valve balls 90 are unseated against the actuating ring 94 in the manner clearly illustrated in Figure 7.

On a reduced end portion 101 of the stud shaft 99 a clamp rotor 10 is mounted for sliding movement in the direction of the axis of said stud shaft. See Figures 8 and 9. The rotor is equipped with diametrically oppositely disposed clearances 103 providing lateral camming flanges 104. The rotor is loosely secured to the valve hub 59 by headed screws 105, and compression spring elements 106 constantly urge the rotor toward said hub.

It will be apparent by reference to Figures 6 and 9 of the drawings that each valve block 80 is equipped with two longitudinally directed duct extensions 107, adjacent duct extensions of the blocks being connected by flexible ducts 108 which are capable of flexing while the blocks are passing around the special sprocket 57 and hub 59 in the manner illustrated in Figure 6 and for the purpose of forming a continuous conduit in which all of the valve blocks are connected. Thus each time a valve ball 90 is unseated, a quantity of inert gas is delivered into the continuous conduit to be delivered therefrom into the gas dispersing thimbles 74 which are traveling along the lower flights of the endless conveyors 50.

In this form of the apparatus, as the open topped containers are rapidly fed along over the supporting rails 8, the gas dispersing thimbles 74 moving in timed relation with and centered over the containers will move downwardly into the containers while moving along the downwardly inclined portions of the chains at 55 and 60 so as to immerse the gas chamber portions 40 in the lower extremities of the thimbles a distance beneath the upper surface of the liquid fill in the containers. The thimbles then move along with the containers in the immersed condition until the end of the apparatus adjacent the closing machine is reached, at which time the thimbles will be lifted out of the containers, the gas dispersion from each thimble being discontinued as it is lifted out of a container. During the immersion of a thimble in a traveling container, the inert gas being dispersed in the liquid fill in the containers just beneath the surface thereof in the form of a multitude of fine jets will cause a multitude of small bubbles to form at the surface of the liquid and rise into the head space in a manner for crowding out all air therefrom and replacing it with the inert gas. The containers with the air thus displaced from the head spaces are then fed to the closing machine wherein they are rapidly closed without air in the head spaces thereof.

An example of the second mentioned type of machine in which there is provided a single, stationary closing station is illustrated in U. S. Letters Patent 1,307,888, issued to Ivar F. Warne on June 24, 1919. A container head space treating apparatus adaptable for use in connection with this type of machine will now be discussed. The machine and the apparatus embodying the invention and mounted thereon are somewhat diagrammatically illustrated in Figure 11 in which figure the said timing means for timing the feed of filled containers to the apparatus is generally designated E, in which the gassing apparatus embodying the invention is generally designated F and the closing machine proper is

designated G. In this form of the apparatus the housing includes a bracket extension 109 which is secured as at 110 to the closing machine. The bracket is an integral part of the gear housing section 111 of the casing, and the gear housing section is secured to a gas dispersing element conveyor housing section 112 which is in turn secured to a flexible gas duct housing section 113 and the latter being in turn secured to a gas supply valve housing section 114 which includes a removable cover portion 115. A shaft housing 116 also is secured between the sections 112 and 114 in the manner best illustrated in Figure 13.

A driver shaft 117 is rotatably mounted in a bearing 118 provided therefor in the housing section 111 and in a bearing 119 provided therefor in the housing section 112. See Figure 16. A driver sprocket 120 is loosely mounted on the shaft 117 and is secured to a driver hub 121 forming the releasable part of an overload release and hand wheel equipment generally designated 122 and which is keyed to the shaft 117. A small spur driver gear 123 is secured to the shaft 117 and meshes with a larger spur gear 124 secured on a shaft 125 which is rotatable in a bearing 126 provided therefor in the housing section 112 and extends through the shaft housing 116 and has rotatable bearing as at 127 in the housing section 114. Within the housing section 114 the shaft 125 carries a driver sprocket 128. See Figures 12 and 13.

A chain passing over the driver sprocket 128 imparts rotation to a sprocket 129 secured on a shaft 130 which is rotatable in a sleeve 131 in a bearing hub 132 formed in the housing section 114. An air or gas seal 133 also is provided for the shaft 130 in the hub 132. See Figures 12, 13 and 16.

A hollow gas manifold rotor 134 is secured to the shaft 130 and is rotatable about the hub 132 and provided with an air or gas seal 135. A gas chamber is formed in the hub 132 surrounding the sleeve 131, and this chamber communicates with the interior of the rotor 134 through a radially disposed port 137 in the hub 132. An inert gas is fed through a duct 138 into the hub chamber 136 and from thence into the rotor 134, the gas being supplied to the duct 138 through a conduit 139 from a suitable supply source (not shown). The rotor 134 is provided with a plurality of supply nipples 140 extending therefrom into the housing section 113, the nipples being equal in number to the number of gas dispersing elements employed in the apparatus and constructed and mounted in the manner soon to be described.

The small spur gear 123 meshes with two larger gears 141 and 142. The gear 141 is secured to a stud shaft 143 which is rotatable in a bearing 144 in the housing section, and the shaft 143 has a sprocket 145 secured thereon within the housing section 112. A chain 146 is driven by the sprocket 145 and passes over idler sprockets 147 and 154, said idler sprockets being rotatable about respective stud shafts 148 and 155 secured as at 149 and 156 respectively to a bearing plate 150 which is slidably mounted as at 151 on the adjacent wall of the housing section 112. See Figures 14 and 17 of the drawings. Screw means 152 are provided for moving the bearing plate 150 in a longitudinal direction, and screw means 153 are provided for securing the plate in adjusted positions.

As the studs 148 and 155 are mounted in fixed positions in the plate 150 their relative posi-

tion will be maintained regardless of any adjustment of the plate 150. A rotor 157 is secured to rotate with the sprocket 147 and is equipped with two diametrically oppositely disposed roller receiving recesses 158. See Figures 14 and 15.

The stud shaft 148 has a reduced end portion 159 which serves as a support for a center roller track member 160 which is secured on said reduced end by a screw 161. The track member 10 includes straightaway guide edge portions 162 and terminates at one end in a half circular end guide edge portion 163 conforming in radius to the depth of the recesses 158 in the rotor 157. The track member 160 has extensive joint connection as at 164 with a main center roller track member 165 which has straightaway edge portions 166 merging with those of the member 160 and which terminates at its other end in a half circular edge portion conforming in radius to the depth of the two roller receiving recesses 168 placed diametrically oppositely in a rotor 169. The rotor 169 is secured to a stud shaft 170 which is rotatably mounted in a bearing 171 in housing section 112 and which also has the driven spur gear 142 secured thereto. The roller track member 165 is screw secured as at 172 to the reduced end 173 of the stud shaft 170 and also as at 174 to spacers extending across the housing section 112. See Figure 15.

30 Upper and lower roller tracks 175 are secured to the housing section 112 and are spaced above and below the outer edges of the roller track member 165 in the manner clearly illustrated in Figure 15 of the drawings. These track elements have end portions 175 extending in partial concentric relation to the half circular edge portion 167 of the inner track member. The track members 175 have extensible joint connection as at 177 with continuation tracks 178 which also 40 are provided with end portions extending in partial concentric relation to the half circular guide edge 163 of the inner track member 160 and which are secured to the adjustably mounted bearing plate 150 so that the track extension portions 178, the inner track member 160 and both sprockets 154 and 147 will move in unison with the plate as it is adjusted.

At equidistantly spaced intervals the chain 146 is provided with sets of mounting pins 180, each 50 set comprising two parallel pins as illustrated in Figure 18. Each set of pins is adapted to engage the receiving sockets 181 provided in an elongated head 182 in a spindle member 183, the pins being secured in the sockets by taper pins 184. By this means the spindles are caused to travel with the chain 146 extending horizontally laterally therefrom in the manner clearly illustrated in Figures 16 and 17 of the drawings.

Each spindle shank is offset or recessed as at 60 185 to clear the inward extensions 179 of the guide track portions 178 and includes a hollow nipple extension 186. An axial bore or duct 187 is provided in each spindle and opens through a radial duct extension in the side wall of the spindle. In this apparatus also the gas dispersing elements are constantly held in the upright position, and to provide for this mounting and control of the elements each element includes a sleeve or hub 188 which rotatably surrounds one of the spindles 183 and has a downwardly directed leg extension 189. See Figure 17. The sleeves 188 are rotatably confined on the spindles by threadably mounted retainer collars 190. Each sleeve extension 189 includes a gas port 191 which communicates during the lower flight only of the

chain with a threadably mounted gas dispensing stem 192 secured in the sleeve extension by a lock nut 193. As in the previously described apparatus, a gasket plug 194 is mounted on the lower end of each stem 192 and serves as a removable friction mounting for a gas dispersing thimble 195 of porous metal or ceramic material. An arm or crank 196 extends horizontally from each sleeve 188 and carries a roller at its free end, said roller being disposed to ride the tracks 175, 166 and the rotor recesses 158 and 168 so as to always hold the arms 196 horizontal and the thimbles 195 vertical.

Gas is supplied from the valve rotor 134 to the individual spindle nipples 186 through flexible ducts 198 which are free to flex within the housing 113, it being understood that the valve rotor nipples 140 move in timed relation with the spindle nipples 186 so as to avoid any interference of the flexible ducts 198 with each other.

It will be observed by reference to Figures 14 and 15 of the drawings that the endless chain supporting sprockets 145 and 154 are offset endwise with respect to the rotors 169 and 157. It will be obvious that since the track guides 175, 178 are horizontally aligned with the upper and lower flights of the chain 146, the crank rollers which are guided by the trackways and the spindles which are carried by the chain will travel in the same horizontal plane throughout the lower and upper flights of the chain, and the manner of offsetting the rotors 157 and 169 with respect to the chain sprockets 154 and 145 will cause the spindle centers and the roller centers to move in the same horizontal plane while passing around the end sprockets, thereby assuring that the gas dispersing thimbles 195 always will be held in the vertical position. In this form of the apparatus the thimbles are lowered into the containers, then move along with the containers and then move out of the containers in the same manner as in the previously described form of the apparatus, the dispersion of the inert gas in the liquid fill serving to form small bubbles effective to rise in the container head spaces and crowd out all air therefrom.

It is of course to be understood that the details of structure and the arrangement of parts may be variously changed and modified without departing from the spirit and scope of the invention.

I claim:

1. In a machine of the character described, means for feeding open liquid filled containers along a straight line, gas delivering elements, means for supplying gas to said elements, endless chain means for supporting said elements and means for moving said chain means through a definite path effective to cause said elements to move down into gassing relation in the head spaces in the containers then move along a distance with the containers while maintaining said relation and then upwardly away from said containers.

2. In a machine of the character described, means for feeding open liquid filled containers along a straight line, gas delivering elements, means for supplying gas to said elements, endless chain means for supporting said elements and means for moving said chain means through a definite path effective to cause said elements to move down into gassing relation in the head spaces in the containers then move along a distance with the containers while maintaining said relation and then upwardly away from said con-

tainers, and control means for controlling the supply of gas to said elements so that they will deliver gas only when in and approximately in said gassing relation with the container head spaces.

3. In a machine of the character described, means for feeding open liquid filled containers along a definite path, gas delivering elements, endless conveyor means for supporting the elements in equidistantly spaced relation and effective for causing said elements in a portion of their endless path of travel to move down into gassing relation in the head spaces in the containers then move along a distance with the containers while maintaining said relation and then move upwardly away from said containers, a flexible conduit connecting all said elements and disposed to follow the path of travel of said endless conveyor means, and means for supplying gas to said conduit.

4. Structure as defined in claim 1 in which each said element comprises a vertically disposed gas delivery stem, a plug gasket surrounding the stem, and a porous walled thimble frictionally embracing the gasket and disposed to have the lower portion thereof presented for immersion in the liquid fill in a container to disperse gas thereinto in a multitude of fine jets.

5. Structure as defined in claim 1 in which each said element comprises a vertically disposed gas delivery stem, a plug gasket surrounding the stem, and a porous walled thimble frictionally embracing the gasket and disposed to have the lower portion thereof presented for immersion in the liquid fill in a container to disperse gas thereinto in a multitude of fine jets, and in which said endless chain means includes devices for constantly holding each said element with its axis uprightly.

6. Structure as defined in claim 3 in which there is included a plurality of rotors for supporting said endless conveyor means, and in which said gas supplying means includes a gas supply duct and a valve actuated each time one of said elements passes around one of said rotors for opening communication between said supply duct and said flexible conduit.

7. In a machine of the character described, means for feeding open liquid filled containers along a straight line, endless chain conveyor means supported to present a lower flight traveling along and over the path of travel of the open container tops, hollow support spindles attached in equidistantly spaced horizontal relation to said conveyor means, a sleeve rotatably surrounding each spindle and having a hollow gas delivery stem depending therefrom centered over the path of travel of the containers, a port in each spindle extending through one wall only thereof centrally over the path of travel of said stems so that each port will communicate with a stem only while traveling along said lower flight, and means for supplying gas to said spindles.

8. Structure as defined in claim 7 in which there is included means for constantly holding each stem with its axis uprightly.

9. Structure as defined in claim 7 in which there is included means for constantly holding each stem with its axis uprightly, and in which there is provided a plug gasket surrounding each stem, and a porous walled thimble frictionally embracing each gasket and disposed to have the lower portion thereof presented for immersion

in the liquid fill in a container to disperse gas thereinto in a multitude of fine jets.

10. In a machine of the character described, means for feeding open liquid filled containers along a straight line, an endless chain and sprocket means for supporting the chain to move in an upright plane with a lower flight passing along with and closely over the open tops of the containers, hollow supporting spindles projecting laterally from said chain, a sleeve rotatably supported on each spindle and having a hollow porous walled gas dispersing element depending therefrom in position for having its lower extremity immersed in the liquid fill of a container during the lower flight travel of the connected chain portion, and means for supplying gas through each spindle and into the gas dispersing element supported thereby.

11. In a machine of the character described, means for feeding open liquid filled containers along a straight line, an endless chain and sprocket means for supporting the chain to move in an upright plane with a lower flight passing along with and closely over the open tops of the containers, hollow supporting spindles projecting laterally from said chain, a sleeve rotatably supported on each spindle and having a gas dispersing element depending therefrom in position for having its lower extremity immersed in the liquid fill of a container during the lower flight travel of the connected chain portion, means for supplying gas through each spindle and into the gas dispersing element supported thereby, and means movable with the chain for holding each sleeve against rotary movement about its axis so as to constantly hold its depending gas dispersing element in upright position.

12. In a machine of the character described, means for feeding open liquid filled containers along a straight line, an endless chain and sprocket means for supporting the chain to move in an upright plane with a lower flight passing along with and closely over the open tops of the containers, hollow supporting spindles projecting laterally from said chain, a sleeve rotatably supported on each spindle and having a gas dispersing element depending therefrom in position for having its lower extremity immersed in the liquid fill of a container during the lower flight travel of the connected chain portion, means for supplying gas through each spindle and into the gas dispersing element supported thereby and including a port opening through one side only in each spindle in line for communicating at times into the connected gas dispersing element, and means movable with the chain for holding each sleeve against rotary movement about its axis so as to constantly hold its depending gas dispersing element in upright position and cause the respective side opening spindle port to communicate into the respective element only during travel along the lower flight of the chain.

13. In a machine of the character described, means for feeding open liquid filled containers along a straight line, an endless chain and sprocket means for supporting the chain to move in an upright plane with a lower flight passing along with and closely over the open tops of the containers, hollow supporting spindles projecting laterally from said chain, a sleeve rotatably supported on each spindle and having a gas dispersing element depending therefrom in position for having its lower extremity immersed in the

liquid fill of a container during the lower flight travel of the connected chain portion, means for supplying gas through each spindle and into the gas dispersing element supported thereby, 5 a crank extending from each sleeve, and holding means engaging all of the traveling cranks and maintaining them constantly in the same relation to the depending gas dispersing elements so as to constantly hold the latter uprightly.

10 14. In a machine of the character described, means for feeding open liquid filled containers along a straight line, an endless chain and sprocket means for supporting the chain to move in an upright plane with a lower flight portion 15 passing horizontally along with and closely over the open tops of the containers there being included two end sprockets one placed at a higher level than the other and an intermediate sprocket placed at the same level as the lower sprocket 20 to define with said lower sprocket said lower horizontal flight portion and a lower flight portion leading in inclined relation downwardly thereto, and gas dispersing elements suspended uprightly from said chain in position for entering 25 the open container tops while traveling along the inclined lower flight portion and remaining therein while traveling along said horizontal flight portion, and means for supplying gas to said elements.

30 15. In a machine of the character described, means for feeding open liquid filled containers along a straight line, an elongated housing having a bottom opening disposed over said feed line, two endless chains and end sprockets supporting them for movement in parallel spaced vertical planes thereby to present upper and lower flights, means to drive said chains to cause the lower flights to travel at the same speed as the containers, two said end sprockets being 35 disposed higher than the remaining two end sprockets so as to offset one chain upwardly with relation to the other, hollow spindles secured at equidistantly spaced intervals to one chain and extending horizontally across toward 40 the other chain, a sleeve rotatably supported on each spindle and having a gas delivering element vertically depending therefrom and an upwardly extended crank arm, means on the other chain for engaging the crank arms and always holding them uprightly, one end sprocket engaged by said one chain having a gas supply port therein, a valve block secured to each spindle and extending inwardly toward the center of the connected chain, flexible ducts connecting said 45 blocks, and valve means unseated during contact of the blocks with said one end sprocket for letting gas into said ducts and the spindles and gas delivery elements connected therewith.

50 16. Structure as defined in claim 15 in which said valve means includes a spring seated ball in each valve block and means for unseating each block ball as it engages said one sprocket as the connected chain is passing therearound.

55 17. Structure as defined in claim 15 in which said valve means includes a spring seated ball in each valve block and means for unseating each block ball as it engages said one sprocket as the connected chain is passing therearound, and in which there is included means for yieldably pressing each valve block laterally against said one sprocket to assure proper unseating of the ball thereof.

60 18. Structure as defined in claim 15 in which said valve means includes a spring seated ball in each valve block and means for unseating each

block ball as it engages said one sprocket as the connected chain is passing therearound, and in which there is included means for yieldably pressing each valve block laterally against said one sprocket to assure proper unseating of the ball thereof, and said one sprocket carries a ball unseating ring having arcuate gas delivery ports therein struck on arcs less than the ball diameter and from centers approximating the point at which each ball engages said ring.

19. Structure as defined in claim 15 in which there are included guide rails one for guiding movement of the valve blocks on said one chain and the other for guiding said other chain during the lower flight travels of both said chains.

20. Structure as defined in claim 15 in which each gas delivery element comprises a vertically disposed gas delivery stem, a plug gasket surrounding the stem, and a porous walled thimble frictionally embracing the gasket and disposed to have the lower portion thereof presented for immersion in the liquid fill in a container to disperse gas thereinto in a multitude of fine jets.

21. In a machine of the character described, means for feeding open liquid filled containers along a straight line, endless chain conveyor means supported to present a lower flight traveling along and over the path of travel of the open container tops, hollow support spindles attached in equidistantly spaced horizontal relation on said conveyor means, a gas delivering element mounted on and supplied with gas from each said spindle, and means for supplying gas to the spindle, said last named means comprising a hollow rotor driven about a horizontal axis in timed relation to said chain and having gas supply nipples extending in equidistantly spaced relation therefrom toward said chain, a flexible conduit connecting each nipple with a chain spindle, and a supply duct for directing gas into said hollow rotor.

22. In a machine of the character described, means for feeding open liquid filled containers along a straight line, endless chain conveyor means supported to present a lower flight traveling along and over the path of travel of the open container tops, hollow support spindles attached in equidistantly spaced horizontal relation on said conveyor means, a gas delivering element mounted on and supplied with gas and from each said spindle, and means for supplying gas to the spindles, said last named means comprising a hollow rotor driven about a horizontal axis in timed relation to said chain and having gas supply nipples extending in equidistantly spaced relation therefrom toward said chain, a flexible conduit connecting each nipple with a chain spindle, a drive shaft supporting said hollow rotor, a bearing hub for said shaft extending into the rotor and having a chamber therein connected through a port with the interior of said rotor, and a supply duct for supplying gas to said chamber.

23. In a machine of the character described, means for feeding open liquid filled containers along a straight line, endless chain conveyor means supported to present a lower flight traveling along and over the path of travel of the open container tops, hollow support spindles attached in equidistantly spaced horizontal relation on said conveyor means, a gas delivering element mounted on and supplied with gas from each said spindle, and means for supplying gas to the spindles, said last named means comprising a hollow rotor driven about a horizontal axis in

timed relation to said chain and having gas supply nipples extending in equidistantly spaced relation therefrom toward said chain, a flexible conduit connecting each nipple with a chain spindle, a supply duct for directing gas into said hollow rotor, and chain and rotor drive means including a power input shaft having a driver gear thereon, a sprocket and stud shaft forming a part of said endless chain conveyor means and having a driven gear thereon meshing with and driven by said driver gear, a rotor driver shaft having a driven gear thereon meshing with and driven by said driver gear, and chain and sprocket connections between the hollow rotor and said rotor driver shaft.

24. In a machine of the character described, means for feeding open liquid filled containers along a straight line, an endless chain and sprocket means for supporting the chain to move in an upright plane with a lower flight passing along with and closely over the open tops of the containers, hollow supporting spindles projecting laterally from said chain, a sleeve rotatably supported on each spindle and having a gas dispersing element depending therefrom in position for having its lower extremity immersed in the liquid fill of a container during the lower flight travel of the connected chain portion, means for supplying gas through each spindle and into the gas dispersing element supported thereby, a crank extending from each sleeve, and means including a recessed rotor moving in timed relation with each chain sprocket and straightaway guide track portions associated with each straight flight portion of the chain for constantly maintaining the cranks in the same relation to the depending gas dispersing elements so as to constantly hold the latter uprightly.

25. In a machine of the character described, means for feeding open liquid filled containers along a straight line, an endless chain and sprocket means for supporting the chain to move in an upright plane with a lower flight passing along with and closely over the open tops of the containers, hollow supporting spindles projecting laterally from said chain, a sleeve rotatably supported on each spindle and having a gas dispersing element depending therefrom in position for having its lower extremity immersed in the liquid fill of a container during the lower flight travel of the connected chain portion, means for supplying gas through each spindle and into the gas dispersing element supported thereby, a crank extending from each sleeve, means including a recessed rotor moving in timed relation with each chain sprocket and straightaway guide track portions associated with each straight flight portion of the chain for constantly maintaining the cranks in the same relation to the depending gas dispersing elements so as to constantly hold the latter uprightly, and an adjustably mounted slide supporting one chain sprocket and one recessed rotor and sections of said straightaway guide track portions.

26. Structure as defined in claim 24 in which said recessed rotors and straightaway track portions are offset in the horizontal-longitudinal direction with respect to the endless chain so as to hold all cranks in the horizontal position.

27. Structure as defined in claim 7 in which said gas supplying means comprises a hollow rotor driven about a horizontal axis in timed relation to said chain and having gas supply nipples extending in equidistantly spaced relation therefrom toward said chain, a flexible con-

duit connecting each nipple with a chain spindle, and a supply duct for directing gas into said hollow rotor.

28. Structure as defined in claim 7 in which said gas supplying means comprises a hollow rotor driven about a horizontal axis in timed relation to said chain and having gas supply nipples extending in equidistantly spaced relation therefrom toward said chain, a flexible conduit connecting each nipple with a chain spindle, a supply duct for directing gas into said hollow rotor, in which there is included a plug gasket surrounding each stem, and a porous walled thimble frictionally embracing each gasket plug and disposed to have the lower portion thereof presented for immersion in the liquid fill in a container to disperse gas therein in a multitude of fine jets, and in which there is included means for constantly holding the stems and the thimbles thereon uprightly.

29. In a machine of the character described, means for feeding open liquid filled containers along a straight line, an endless chain and sprocket means for supporting the chain to move in an upright plane with a lower flight passing along with and closely over the open tops of the containers, hollow supporting spindles projecting laterally from said chain, a sleeve rotatably supported on each spindle and having a gas dispersing element depending therefrom in position for having its lower extremity immersed in the liquid fill of a container during the lower flight travel of the connected chain portion, means for supplying gas through each spindle and into the gas dispersing element supported thereby, a crank extending horizontally from each sleeve and having a roller at the free end thereof, and means including two rotors recessed at their peripheries to receive the crank rollers and offset longitudinally-horizontally with respect to the endless chain and inner and outer trackways for guiding movement of said rollers to always hold said cranks horizontally, said inner trackway having straightaway upper and lower edge portions and half circular end portions conforming in radius to the radius of the depth of the rotor recesses, and said outer trackways having upper and lower straightaway portions in spaced parallel relation to said inner trackway upper and lower edge portions.

30. In a machine of the character described, means for feeding open liquid filled containers along a straight line, an endless chain and sprocket means for supporting the chain to move in an upright plane with a lower flight passing along with and closely over the open tops of the containers, hollow supporting spindles projecting laterally from said chain, a sleeve rotatably supported on each spindle and having a gas dispersing element depending therefrom in position for having its lower extremity immersed in the liquid fill of a container during the lower flight travel of the connected chain portion, means for supplying gas through each spindle and into the gas dispersing element supported thereby, a crank extending horizontally from each sleeve and having a roller at the free end thereof, and means including two rotors recessed at their peripheries to receive the crank rollers and offset longitudinally-horizontally with respect to the endless chain and inner and outer trackways for guiding movement of said rollers to always hold said cranks horizontally, said inner trackway having straightaway upper and

lower edge portions and half circular end portions conforming in radius to the radius of the depth of the rotor recesses, and said outer trackways having upper and lower straightaway portions in spaced parallel relation to said inner trackway upper and lower edge portions and end portions bearing part concentric relation to the recessed rotors, and said spindles having recesses therein to clear said outer trackway end portions where chain straightaway portions extend endwise beyond said outer trackways.

31. In a machine of the character described, porous walled gas dispersing elements, means for causing said elements and open filled containers to move together along a path of travel with an element centered over each container, means for bringing about relative movement between the traveling elements and containers to cause said elements to be immersed a limited distance in the fill in the containers, travel along a distance so immersed in the containers and then be withdrawn from said immersion, and means for directing inert gas into said elements to be dispersed through the porous walls thereof.

32. In a machine of the character described, means for feeding open liquid filled containers along a straight line, gas delivering elements, means for supplying gas to said elements, and endless chain means for supporting said elements and effective to cause said elements to move down into gassing relation with the head spaces in the containers then move along a distance with the containers while maintaining said relation and then upwardly away from said containers, said endless chain means comprising two laterally spaced endless chains each traveling about two sprockets, the sprockets supporting one chain being rotatable about axes disposed in a horizontal plane below the horizontal plane in which the axes of the sprockets supporting the other chain are located, said gas delivering elements being elongated and each having two pivotal connections arranged in a common vertical plane and one connected to one chain and the other to the other chain, and the sprockets at each end of the two cooperating chains having their axes disposed in a common vertical plane.

33. A machine structure as defined in claim 1 in which each chain supported gas delivering element has associated therewith a nipple extension, and in which the means for supplying gas to said elements comprises a hollow rotor rotating in timed relation with the chain and having gas supplying nipples extending therefrom in equidistantly spaced relation and equal in number to the chain borne nipple extensions, means for supplying gas to the rotor, and a flexible duct connecting each rotor nipple with one of the chain borne nipple extensions.

34. A machine structure as defined in claim 1 in which said endless chain means comprises a single endless chain, spindles projecting horizontally and in equidistantly spaced relation from the chain, sleeves rotatably mounted on the spindles and from which the gas delivering elements depend vertically, crank members projecting from the sleeves, and guide means for constantly holding the cranks in a definite relation to said elements for constantly holding said elements uprightly.

ALFRED L. KRONQUEST.
